CLAIM

The ornamental design for a paper feed mechanism for a printer, typewriter, or the like, as shown and described.

DESCRIPTION

FIG. 1 is a front right perspective view of a paper feed mechanism for a printer, typewriter, or the like showing my new design, the broken line disclosure of paper and printer being illustrative of environment only; FIG. 2 is a top rear left perspective view; and FIG. 3 is a top left perspective view. The unseen bottom surfaces are unornamented.
